KERF-CUTTING MACHINE

Frank A. Lindgren, Western Springs, Ill., assignor
to Goodman Manufacturing Company, Chi-
cago, Ill., a corporation of Illinois

Application August 16, 1934, Serial No. 740,109

8 Claims. (Cl. 262—30)

This invention relates to improvements in kerf-cutting machines, and more particularly to kerf-cutting machines of the type that are slideable bodily upon the mine bottom while cutting; as, for instance, such machines of the continuous cutting and longwall types.

The principal object of the present invention is to provide an improved form of device for tilting the machine, or holding it in various angular adjustments with respect to the mine floor while cutting a kerf. More specifically, the invention consists in providing a novel form of tilting shoe which can be readily attached or detached from the body of the kerf-cutting machine, and is also capable of being changed into reversed position, so as to tilt the machine in either direction of cutting.

Other objects of the invention will also appear from the following detailed description of one embodiment of my invention, having reference to the accompanying drawing, in which:

Figure 1 is a plan view of a kerf-cutting machine of the continuous cutter type, to which my improved tilting device has been applied;

Figure 2 is a rear view of the machine shown in Figure 1, with parts of the tilting device broken away to show details of construction thereof;

Figure 3 is a fragmentary side view of the machine showing the rear end thereof and the tilting device in partial section.

Referring now to details of construction of the embodiment of the invention shown in the drawing, the same is shown as applied to a kerf-cutting machine of the continuous cutter type, consisting of a cutter bar 10 with an endless cutter chain 10^a of the usual type thereon, and a body portion 11 including a motor 12 with gearing at the forward end for driving the cutter chain, and other gearing in a frame member 13 at the rear end thereof for driving feed rope drums 14 and 15. The cutter chain and feed rope drum drive gearing may be of any well-known form, and since they form no part of the present invention they need not be shown nor described in detail herein.

The rope drums 14 and 15 are provided with flexible cables 16 and 17, respectively, which may be selectively trained, as usual, in various arrangements about guide sheaves 18 or 19 at the forward end of the machine, or sheaves 20, 21 or 22 at the rear end of the machine, for the purpose of moving the machine over the mine floor in its cutting operations. It will, of course, be understood that during such movements, the body 11 of the machine is supported for sliding directly on the mine bottom.

Referring now more particularly to the novel features of my improved form of tilting device, the same is indicated generally at 25, and is here shown as applied to the rear end of the machine.

The device consists of a plate 26 forming a shoe for engagement with the mine floor, and supported on the body of the machine by detachable connecting devices, one consisting of a hinge member 27 and the other consisting of a vertical adjusting member 28.

The hinge member 27 comprises an upright supporting link 29 pivoted on a pin 30 carried in a boss 31 extending upwardly from the plate 26 and permanently secured thereto, as by welding. The pin 30 is disposed transversely of the plate 26 and longitudinally of the machine body 11, as shown. The upper end of the link 29 is preferably formed integral with a block 32, which is interchangeably connectible with a pair of brackets 33, 34 projecting from the rear frame portion 13 of the machine at equal distances from the longitudinal axis of the latter. In the position shown in the drawing, the hinge block 32 is connected to the left-hand bracket 33, as viewed from the rear of the machine in Figure 2. The connection is afforded by providing said block with flanges 32^a and 32^b at the upper and lower side edges thereof, and arranged so that the entire block is removably fitted between laterally spaced, rearwardly extending arms 33^a and 33^b of the bracket 33, as clearly shown in Figures 1 and 2. The block is held in place by suitable means, such as a retaining bar 35 held by removable pins 36, 36 to lugs 37, 37 at opposite sides of 30 the bracket 33.

As will be seen in Figure 2, the inner faces of the arms 33^a and 33^b are preferably formed in convex shape where they engage the opposite sides of the hinge block 32, so as to afford comparative freedom of lateral rocking movement of said block and its associated hinge connection relative to the machine.

The adjusting member 28 of the shoe 26 is provided with a detachable block 42 which is of substantially the same size and shape as the block 32 of the hinge member 27. The arrangement is therefore such that the blocks 32 and 42 may be interchangeable with respect to the brackets 33 and 34, by removing said blocks from the brackets, 45 reversing the plate 26, end for end, and replacing said blocks in the opposite brackets.

The vertical adjusting means consists of a screw 43 depending from the block 42 and suitably secured from rotation therein, as by pin 44. Said screw extends downwardly and is threaded in a nut 46, rotatably mounted on a boss 45 secured to the plate 26. Said nut has bearing on a base portion 47 of said boss, as clearly shown in Figures 2 and 3. An anti-friction device 49 of the usual ball-bearing type may be housed within the base 47 of said boss, and the nut 46, together with said anti-friction device, may be retained in position by an upper extension 48 of said boss, so long as the screw 43 is threaded therein. This verti- 60

cal adjusting device may thus be permanently carried by the shoe, and the anti-friction means facilitates adjustment of the tilting device.

The use and operation of the tilting device will now be understood. When the kerf-cutting machine is being operated so as to cut from right to left, as viewed in Figure 2, the hinge member 27 is preferably disposed, as shown in the left hand bracket 33. With this arrangement, the nut 46 5 may be turned so as to depress the plate or shoe 26 any desired amount, thus producing a corresponding elevation of the right side of the machine, and a downward inclination of the cutter bar 18 with respect to the mine bottom in the direction of cutting. It will be observed that the plate 26 hinges about a substantially fixed axis disposed at the left side of the machine bottom, but the curved shape of the arms of the brackets 33 and 34 affords substantial freedom of lateral 10 movement of the hinge pin 30 and rocking movement of adjusting screw 43, so as to readily accommodate the latter to various angular positions of adjustment of the tilting plate.

When it is desired to feed the machine for cutting in the opposite direction, or from left to right, the tilting plate is reversed end-to-end with the blocks 32 and 42 in mutually reversed positions. Moreover, when the tilting device is not needed, it can be easily removed as a unit from 15 the machine, and again replaced when required.

It will be further understood that the tilting device can also be connected at other points intermediate the ends of a machine of the character here illustrated, and may also with slight modifications be used on other types of machines, such as the longwall machine, in which type it may be convenient to extend it lengthwise of the body of the machine, as the cutter bar usually extends in cutting position from the side of the 20 machine.

Although I have shown and described one form in which my invention may be embodied, I do not wish to be limited to the precise details of construction or arrangement of parts herein 25 shown and described, nor to the embodiment herein illustrated, excepting as specifically limited in the appended claims.

I claim as my invention:

1. In combination with a kerf-cutting machine 30 slidable on its own bottom on the mine floor, a shoe adapted to engage the mine floor, means for detachably connecting said shoe to said machine comprising means interchangeably connectible to said machine adjacent opposite sides of the latter, hinge means disposed between said shoe and one of said connecting means, and vertical 35 adjusting means disposed between said shoe and the other of said connecting means.

2. In combination with a kerf-cutting machine 40 slidable on its bottom on the mine floor, a shoe adapted to engage the mine floor, means connecting said shoe to said machine comprising two brackets rigidly connected to said machine and two members detachably fitting into said brackets 45 to permit relative lateral rocking movement therebetween, one of said members having hinged connection with said shoe, and the other of said members having vertical adjustment relative to said shoe.

3. In combination with a kerf-cutting machine 50 slidable on its own bottom on the mine floor, a shoe adapted to engage the mine floor, means interchangeably connecting the shoe to said machine in end-to-end reversed relation comprising

a pair of similar brackets rigidly connected to said machine, two similarly shaped members detachably fitting from either side in supporting relation in said brackets, one of said members having hinged connection with said shoe and the other of said members having vertical adjustment relative to said shoe. 5

4. In combination with a kerf-cutting machine 10 slidable on its own bottom on the mine floor, a shoe adapted to engage the mine floor, means interchangeably connecting the shoe to said machine in end-to-end reversed relation comprising a pair of similar brackets rigidly connected to said machine, two similarly shaped members detachably fitting from either side in supporting 15 relation in said brackets, one of said members having hinged connection with said shoe and the other of said members having vertical adjustment relative to said shoe and both of said members having limited rocking movement in their 20 respective brackets in the plane of hinged movement of said shoe.

5. In combination with a kerf-cutting machine 25 slidable on its bottom on the mine floor, a shoe extending across the rearward end of the machine adapted to engage the mine floor and form a continuation of the bottom of the machine, a boss mounted adjacent one end of said shoe, a nut engaging said boss, a screw threaded in said nut, means detachably connecting the upper end 30 of said screw in supporting relation to said machine, and hinge means detachably connecting the opposite end of said shoe in supporting relation to said machine. 35

6. In combination with a kerf-cutting machine 40 slidable on its bottom on the mine floor, a shoe adapted to engage the mine floor, a boss mounted adjacent one end of said shoe, a nut engaging said boss, a screw threaded in said nut, means detachably connecting the upper end 45 of said screw in supporting relation to said machine, and hinge means detachably connecting the opposite end of said shoe in supporting relation to said machine. 50

7. In combination with a kerf-cutting machine 55 slidable on its bottom on the mine floor, a shoe adapted to engage the mine floor, a boss mounted adjacent one end of said shoe, a nut engaging said boss, a screw threaded in said nut, means detachably connecting the upper end 60 of said screw in supporting relation to said machine, and hinge means detachably connecting the opposite end of said shoe in supporting relation to said machine, the detachable connecting means for said screw and said hinge means being mutually interchangeable with said shoe in reversed end-to-end relation relative to said machine.

8. In combination with a kerf-cutting machine 65 slidable on its bottom on the mine floor, a shoe adapted to engage the mine floor, a boss mounted adjacent one end of said shoe, anti-friction means housed in said boss, a nut rotatably mounted on said anti-friction means, means holding said nut from vertical displacement relative to said boss, a vertically disposed screw 70 threaded in said nut and having its upper end connected to said machine, and hinge means connecting the opposite end of said shoe to said machine. 75
